United States Patent Office

Des. 182,311
Patented Mar. 11, 1958

182,311

PENCIL OR LIKE ARTICLE

Harold E. Steinberg, Philadelphia, Pa., assignor to The Esterbrook Pen Company, Camden, N. J., a corporation of New Jersey

Application July 19, 1957, Serial No. 47,003

Term of patent 14 years

(Cl. D74—24)

Figure 1 is a side elevational view of a pencil or like article according to my new design;

Fig. 2 is a front elevational view of the same;

Fig. 3 is a fragmentary rear elevational view of the upper portion thereof; and

Fig. 4 is a top plan view thereof.

I claim:

The ornamental design for a pencil or like article, substantially as shown.
